(57) **CLAIM**

The ornamental design for a sensor attachment accessory as shown and described.

DESCRIPTION

FIG. 1 is front view of a sensor attachment accessory according to the claimed design.

FIG. 2 is a rear view of the sensor attachment accessory.

FIG. 3 is a left side view of the sensor attachment accessory.

FIG. 4 is a right side view of the sensor attachment accessory.

FIG. 5 is a bottom view of the sensor attachment accessory.

FIG. 6 is a top view of the sensor attachment accessory.

FIG. 7 is a top front right perspective view of the sensor attachment accessory with a wireless sensor in environment; and,

FIG. 8 is bottom rear left view of the sensor attachment accessory with the wireless sensor shown in environment. The broken lines of FIGS. 7–8 illustrate environmental matter that form no part of the claimed design.

The repeating hook-shaped patterning shown by FIG. 1 and FIG. 7 represents hook-and-loop material that forms no part of the claimed design.

The stipple shading in FIG. 2 represents an adhesive that forms no part of the claimed design.
